CARBURETOR FOR INTERNAL-COMBUSTION ENGINES

Application filed October 12, 1928, Serial No. 312,140, and in the Union of South Africa June 2, 1928.

This invention relates to carburetors for internal-combustion engines.

The object of the invention is to design the carburetor so as to obtain a more economical use or consumption of the petrol or other liquid fuel (hereinafter referred to as petrol) and consequent higher efficiency in the engine or motor.

To the attainment of this object the invention includes means for more effectively comminuting or atomizing the petrol; means for controlling the supply of the petrol to said comminuting or atomizing means; means for controlling the volume of air which is admitted for mixing with the comminuted or atomized petrol; and means for controlling the passage of the explosive mixture of air and atomized petrol to the engine or motor.

According to the invention the means for comminuting or atomizing the petrol comprises or includes a part or member constructed to provide a fine or narrow slot or slit of such a width that the petrol by its passage therethrough under normal pressure or conditions will be comminuted or atomized to a very high degree.

The means for controlling the supply of the petrol to the slot or slit may be designed so as to admit of any desired portion of the length of said slot or slit being closed or cut off, and so that the remaining portion only functions to control the supply of the petrol.

The part or member forming the slot or slit for the passage of the petrol may be of tubular form, having a flat piece or surface in which the slot or slit is suitably formed. As it is essential that this slot or slit should be exceedingly fine or narrow, we have found that possibly the simplest way of making the slot or slit in the flat piece or surface is by forming a cut or slit in the piece for a suitable portion of its length, then bending the portion of the piece at one side of the cut or slit away from the other side, in such a way that either or both edges formed by the cut or slit can be filed to the requisite extent to leave or make the slot or slit of the requisite width, after which the bent portion is bent back to its normal position.

The means for controlling the supply of petrol passing to and through the slot or slit may include a cylindrical member or valve which fits the tube and is constructed with a bevelled or tapered portion forming a knife edge or edges which, when the valve is rotated, are adapted to co-operate with the slot or slit in order to close or cut off any desired portion of the length of the slot or slit. This valve is constructed to form a passage for the petrol leading through it to a point in the bevelled surface or face. The tube and the cylindrical member or valve are housed in or carried by a casting or part forming the carburetor casing, which provides the passage leading from the air control valve to the valve which controls the passage of the explosive mixture to the engine.

The valve for controlling the admission of air and the valve for controlling the admission of the explosive mixture to the engine are preferably both in the form of hollow cylindrical or sleeve valves.

The valve controlling the supply of petrol to the comminuting or atomizing device, the valve for controlling the supply of air, and the valve for controlling the supply or passage of the explosive mixture to the engine are preferably adapted to be actuated by a single control or operating means.

The valve controlling the supply of petrol and the valve controlling the supply of air are constructed and set, for the normal operation of the engine or motor, so that the proportion of air to petrol remains fixed or constant, for all positions of the valves, while the valve which controls the passage of the explosive mixture to the engine is opened proportionately to the opening of the other valves. This ensures that the proportion of petrol to air is constant for all speeds of the engine, but that the speed of the engine is increased by increasing the volume or quantity of the mixture which passes thereto.

Means is provided for independently actuating the valve controlling the petrol supply to obtain an enriched mixture, or to allow of an increase in the quantity of petrol relative

to the volume of air, for the purpose of starting the engine, or whenever else necessary.

The invention will be more fully explained with the aid of the accompanying sheet of drawings, wherein a practical embodiment of the same is illustrated. In the drawings, 5

Fig. 1 is a sectional elevation of the carburetor taken centrally through the three valves.

10 Fig. 2 is a sectional plan, the plane of section being indicated by the dotted line 2—2 in Fig. 1.

Fig. 3 is an elevation of the complete carburetor drawn to a reduced scale.

15 Fig. 4 is an elevation of the member providing the slot or slit for atomizing the petrol.

Fig. 5 is a sectional plan on the dotted line 5—5, Fig. 1, and

20 Fig. 6 is two views at right angles of the petrol controlling valve.

In Figs. 1, 2 and 3 of the drawings the numeral 1 denotes a casting which forms the casing or housing for the several valves hereinafter described. The casing 1 includes the 25 two hollow cylindrical parts 2, 3, and the intermediate rectangular connecting portion 4. 5 is the float-feed chamber which is constructed with an arm or projection 6, the outer end of which is fashioned with a conical recess 7 30 to fit a tapered projection 8 formed on the part 4 of the casing 1. The arm 6 is retained in position on the tapered projection 8 by a screw plug 9. The petrol from the float-feed chamber 5 passes into the space 10 provided by the bottom of the recess 7 below the inner 35 end of the projection 8. The plug 9 is provided with a passage 11 through which the petrol can pass from the space 10 to the inner end of the plug 9.

40 12 is the tubular part or member which is housed in the part 4 of the casing 1 and is constructed at the one end with a flange or shoulder 13 which fits against the inner end of the screw-threaded hole in the tapered 45 projection 8. The tubular part 12 is held in position by means of the screw plug 14 which is tapered at its inner end and screwed into engagement with the flanged end of the tubular part 12. The screw plug 14 is provided 50 with a hole 15 which forms a passage for the petrol from the inner end of the plug 9 into the lower end of the tubular part 12. The upper portion 16 of the tubular part 12 is tapered slightly—see also Fig. 4—and fits a 55 correspondingly tapered hole formed in an exteriorly screw-threaded boss 17 on the part 4 of the casing 1. 18 is the piece in which the fine or narrow slot or slit 19 is formed. As shown the piece 18 is in the form of a flat 60 plate fixed in an opening in the side of the tubular part 12. The slot or slit 19 is shown provided in the lower portion of the plate 18, and may be formed therein in the manner hereinbefore explained, or in any other suitable and preferred manner.

20 (see also Fig. 6) is the cylindrical member or valve which regulates or controls the quantity of petrol which passes through the slot or slit 19 into the part 4 of the casing 1. This valve 20 is positioned in the tubular part 12 and is fashioned at its inner end with a bevelled or tapered portion 21, the edges of which are adapted to co-operate with the slot or slit 19 in order to close or cut off any desired portion of the length of the slot or slit 19 to vary or regulate the quantity of petrol passing through said slot or slit 19. The edges of the valve 20, by working in contact with the inner surface of the plate 18, remove any adhering foreign matter from the plate 18 and prevent choking or closing of the slot or slit 19 thereby. The lower inner end of the valve 20 is shown of cylindrical shape so that it serves as a guide for the valve below the bottom of the bevelled portion 21. 22 is a hole or passage which extends through from the inner end of the valve 20 and opens in the bevelled face 21. The passage 22 permits the petrol to pass to the slot or slit 19 from the space in the tubular part 12 below the inner 70 end of the valve 20. The valve 20 is shown constructed with a flange 23 which, when said valve is in position, is seated in a recess 24 formed in the boss 17 above the upper end of the tubular part 12, the stem of the valve 75 extending upwardly beyond the flange 23.

In the hollow cylindrical part 2 of the casing 1 is arranged the air inlet valve 25 which, as shown, is in the form of a rotary hollow cylindrical or sleeve valve constructed with a 80 port or passage 26 which is adapted to control the passage of air from the part 2 to the part 4 of the casing 1. 27 is a cap screwed on to the lower end of the part 2, which serves for retaining the sleeve valve 25 in position. The valve 25 is constructed at its lower 85 end with a stem 28 for rotating it.

In the hollow cylindrical portion 3 of the casing 1 is arranged the valve 29 which controls the passage of the explosive mixture to the engine. This valve 29 is also in the form of a rotary hollow cylindrical or sleeve valve, provided with a port or passage 30 which is adapted to control the passage of the explosive mixture from the passage through the part 4 to the engine. This valve 29, like the valve 25, is constructed with a stem 31 for rotating it, which stem 31 passes through a hole 32 in the bottom of the portion 3 of the casing 1.

The means for simultaneously rotating the petrol supply valve 20, the air supply valve 25, and the explosive mixture supply valve 29 includes, for each valve, a lever 33, 34, 35, respectively, which levers at one end are constructed in the form of a clevis or clamp for clamping them to their respective valve stems after the valves have been set in the requisite positions to ensure the correct proportions of air to petrol, and volume of explosive mix- 130

ture which passes to the engine. Split pins 36, 37, are shown passing through the stems 28, 31, respectively, below the clamping ends of the levers 34, 35. The several levers 33, 34, 35 are operated simultaneously by means connected say to the outer end 39 of the lever 35. The means for connecting the levers 33, 34, 35, is shown including a yoke piece 38, which engages in holes formed in the levers 34, 35, and is retained in position therein by the split pins 40, and a rod 41 attached to the yoke piece 38 at the centre thereof and at right angles thereto by the coupling piece 42. The upper end of the rod 41 engages in a hole in the outer end of the lever 33.

The auxiliary means for operating the petrol supply valve 20, independently of the normal actuating means through the lever 33, is shown including a nut 43 which has screw-threaded engagement with the threaded boss 17, a pin 44 fixed at one end in one of a plurality of screw-threaded holes 45 (for adjusting purposes), and a wire 46, attached by means of a connecting piece 47 to the pin 44. The wire 46 passes through a flexible casing 48 to any desired point where it will be readily accessible to the driver of the vehicle. 49 is a clamp bracket for attaching the casing 48 to the side of the part 3 of the casing 1 opposite the end of the pin 44. By moving the wire 46 in the one direction, the nut 43 is rotated and the valve 20 lifted thereby without being rotated. This ensures the slot or slit 19 being opened to a greater extent than it would be when normally operated with equal angular movement. In this way a richer mixture is obtained for starting the engine or motor. Movement of the wire 46 in the opposite direction, by lowering the valve 20, will reduce the quantity of petrol to normal. 50 is a cap fixed by pin 51 on the upper end of the stem of valve 20, above the clevis or clamp end of the lever 33. This cap 50 has a milled edge to enable it to be used for setting or adjusting the petrol supply valve 20.

52 is a washer arranged between the flange 23 on the valve 20 and the inwardly directed flange 53 on the nut 43, which washer ensures the valve 20 being lowered when the nut 43 is rotated in the requisite direction.

What we claim as our invention and desire to protect by Letters Patent is:—

1. In a carburetor for internal combustion engines, in combination, a hollow cylindrical member having a very narrow slit through which the liquid fuel passes before being mixed with the air to form the explosive mixture, and a rotary cylindrical valve having a tapered portion which provides an inclined edge which directly co-operates with the slit to vary the effective length of said slit in order to control the quantity of liquid fuel which passes through the slit, as set forth.

2. In a carburetor for internal combustion

engines, in combination, a hollow cylindrical member having a very narrow slit through which the liquid fuel passes before being mixed with the air to form the explosive mixture, and a rotary cylindrical valve constructed with a tapered flat face which forms a recess and an inclined edge to co-operate with the slit, and with a passage extending from one end of the valve to the recess formed at the back of the slit by the tapered flat face, the inclined edge directly co-operating with the slit to vary the effective length thereof in order to control the quantity of liquid fuel which passes through the slit, as set forth.

3. In a carburetor for internal combustion engines, in combination, a hollow member having a narrow slit through which the fuel passes before being mixed with the air to form the explosive mixture, a rotary cylindrical valve having a tapered portion which provides an inclined edge which directly co-operates with the slit to vary the effective length of said slit in order to control the quantity of liquid fuel which passes through the slit, and means for rotating the valve for normal operation, and means for raising and lowering the valve, as set forth.

4. In a carburetor for internal combustion engines, in combination, a hollow member having a narrow slit through which the fuel passes before being mixed with the air to form the explosive mixture, a rotary cylindrical valve having a tapered portion which provides an inclined edge which directly co-operates with the slit to vary the effective length of said slit in order to control the quantity of liquid fuel which passes through the slit, means for rotating the valve for normal operation, and means for raising and lowering the valve including a threaded boss formed on the carburetor casing, a nut engaging said boss and rotatably engaging the valve, and hand-actuated means for rotating the nut, as set forth.

5. A carburetor for internal combustion engines, including, in combination, a hollow member in which is formed a narrow slot through which the liquid fuel passes before being mixed with the air to form the explosive mixture, a rotary cylindrical valve constructed with a tapered portion directly co-operating with the slot to control the quantity of liquid fuel which passes through the slot, a rotary sleeve air admission valve, and a rotary sleeve valve for controlling the passage of the explosive mixture from the mixing chamber to the engine, and means for simultaneously operating all of said valves, as set forth.

In testimony whereof we have signed our names to this specification.

WILLIAM HASLAM MANNERS.
CECIL WHESTHEAD SPENCER.
